BATTERY CABLE CONNECTOR

Clive D. Ahearn, Detroit, Mich.

Application December 8, 1938, Serial No. 244,671

1 Claim. (Cl. 173—259)

My invention relates to improvements in storage battery cable terminals, whereby both a strong grip on the battery post and easy removal from the battery post is produced by mechanical manipulation of a part of the connector, and an important object of my invention is to provide a simple and efficient and practical arrangement of the character indicated.

Other important objects and advantages of my invention will be apparent from a reading of the following description taken in connection with the drawing, wherein for purposes of illustration I have shown a preferred embodiment of my invention.

15 In the drawing:—

Figure 1 is a top plan view of a portion of a storage battery showing the device of the invention connected thereto.

Figure 2 is a side elevational view of Figure 1. 20 Figure 3 is a horizontal sectional view taken through Figure 2 approximately on the line 3—3.

Figure 4 is a horizontal sectional view taken through the upper part of Figure 5 and approximately on the line 4—4 and looking downwardly.

25 Figure 5 is a transverse vertical sectional view taken through Figure 1 approximately on the line 5—5.

Referring in detail to the drawing, the numeral 5 generally designates the embodiment of the 30 present invention which comprises two substantially semi-cylindrical sections respectively denominated by the numerals 6 and 7. Each of these sections has semi-annular laterally outwardly projecting portions affording the respective shoulders 8 and 9 on which the rotary cam 10 bears, these sections also having the L-shaped flanges 11, 12, respectively, which overlie the shoulders 8 and 9 and confine the rotary cam 10 in place. The section 7 has projecting radially 35 therefrom below the shoulder 9 a tubular arm 13 which is adapted to be telescoped on and secured to the terminal of the battery cable 14.

The terminal edges of the section 6 have aligned ears 15, 16 which project therefrom along 40 and at the inner side of ears 17, 18 projecting from the section 7 in a position circumferentially outwardly spaced from the ears 15, 16, and suitable pivots such as rivets 19, 20 traverse the respective pairs of ears 15, 17 and 16, 18 so as to 45 pivotally connect the sections. The ears 15, 16 project into and in spaced relation to notches 21 formed in the terminal edges of the section 7 as illustrated in Figure 5.

The rotary cam 10 is oval in shape and provided with a stem 22 which rises from the cen- 50 tral portion of the cam 10 and terminates in a 55

ter thereof and is equipped with a turning handle 23. A stop post 24 projects from the section 11 at the top thereof to be in the way of one or the other end of the handle 23 so as to limit the rotating action of the cam in either direction 5 beyond a full rotation thereof.

The grooves in the sections 6 and 7 defined by the L-shaped flanges 11 and 12 and the shoulders 8 and 9 are formed on such radii of curvature, and the sections so spaced with respect to each other that when the long axis of the cam 10 lies along the opening between the sections the sections are permitted to tilt toward each other at the top thereof as illustrated in Figure 5 and thereby spread the bottom of the sections to 15

readily and easily receive the battery post 25 on the battery 26. Therefore, with the connector installed on the battery post turning of the handle 23 to bring the cam into the stated position 20 will operate to release the sections from clamping engagement with the sides of the battery post so as to facilitate removal of the connector from the post.

On the other hand, the connector having been installed with great ease on the battery post 25 because of the spread of the lower ends 25 of the sections of the connector, the sections are brought into clamping relation with the sides

of the battery post by operating the handle 23 to bring the cam out of alignment with the opening 30 between the sections and into a turned position such as illustrated in Figure 4, wherein the ends of the cam bear against the grooves mentioned and force the tops of the sections away from each other on the axis of the pivots 19, 20 and thereby force the lower part of the sections forcibly 35 against the sides of the battery post so as to effect an efficient clamping action.

Although I have shown and described herein a preferred embodiment of my invention, it is to be definitely understood that I do not desire 40 to limit the application of the invention thereto, and any change or changes may be made in the structure and arrangement of the parts, within the spirit of the invention and the scope of the subjoined claim.

Having described the invention, what is 45 claimed as new is:—

A battery cable connector comprising a pair of semi-cylindrical members for fitting around a battery post, means for connecting a cable to one 50 member, each member having a flange-like enlargement at its upper end formed with an internal groove, one member at the substantial central portion being thicker than the other member and said thickened portion having internal 55

recesses at its edges, ears extending outwardly from edge portions of the other member and said ears extending into the recesses, the recessed portions of the thick member forming ears which
5 overlap the first-mentioned ears, pivots pivotally connecting the ears of the two members together,

an oval cam forming plate having portions extending into the grooves at the upper ends of the two members and a handle part connected with the plate and extending upwardly.

CLIVE D. AHEARN.
